UNITED STATES PATENT OFFICE.

JOHN A. KAYE, OF SAULT STE. MARIE, ONTARIO, CANADA; CLARA KAYE EXECUTRIX
OF SAID JOHN A. KAYE, DECEASED.

FOUNTAIN PEN.

Application filed November 5, 1925. Serial No. 67,049.

The present invention relates to a fountain pen and has for its object to provide a device of this character which embodies novel features of construction whereby the flow of ink to the pen point is under control and can easily be increased or decreased while the pen is in use and without any interruption to the writing operation.

The invention further contemplates the provision of a pen of this character which is simple and inexpensive in its construction, which can be used without soiling the fingers, and which can be easily manipulated while in use to increase or decrease the flow of ink to the pen point, as may be desired.

While one particular embodiment of the invention will be shown and described in detail for illustrative purposes, it will be understood that many modifications and changes can be made in the details of construction without departing from the spirit and scope of the invention.

For a full understanding of the invention reference is to be had to the following description and accompanying drawings in which:

Fig. 1, is an enlarged longitudinal sectional view through the ink feeding end of the fountain pen.

Fig. 2, is a side elevation of one end of the fountain pen, looking downwardly upon the slide which controls the feeding of the ink to the pen point.

Fig. 3, is a detail view of the wire stem which projects from the valve for controlling the flow of ink.

Corresponding and like parts are referred to in the following description and indicated on all of the views of the drawings by like reference characters.

Referring to the drawings, the numeral 1 designates the barrel of the fountain pen which forms a reservoir to receive a supply of ink and is closed at its rear end by means of a cap. This cap can be readily removed at any time when it is desired to fill the reservoir with ink.

The other end of the tubular barrel 1 has a plug 4 fitted therein to close the same. This plug is formed with a suitable opening or seat to receive the rear end of the pen point 5 and has an ink feeding passage 6 therein which extends under the forward end of the pen point and communicates at

its rear end with a chamber 4^a which is 55 formed in the rear end of the plug.

The forward end of the ink feeding passage 6 extends to a point slightly beyond the eye 7 of the pen point and the rear end of the ink feeding passage is flared to provide a valve seat 8. A tapered valve 9 is movable toward and away from the said valve seat to regulate the flow of ink through the passage 6.

A wire stem 10 which is connected to the valve 9 extends forwardly through the ink feeding passage 6 and terminates in a perforated head 10^a which is adapted to receive a lateral arm 11 projecting through the eye 7 of the pen point. This lateral arm 11 is 70 carried by a stem 12 projecting from the end of a slide 13 which is mounted in a channel 14 formed in the barrel 1 and extending longitudinally thereof. The slide preferably has the outer surface thereof roughened so 75 that it can be readily engaged by one of the fingers of the hand to move the same longitudinally of the barrel thereby moving the valve 9 toward or away from the valve seat and decreasing or increasing the flow of ink, 80 as may be desired. The end of the barrel 1 is formed with an annular enlargement or rib 15 which tends to prevent the fingers from being moved downwardly over the end of the barrel and smeared with ink by 85 being brought into engagement with the pen point. This annular rib or enlargement is formed with a suitable guide opening through which the member 12 passes.

When the pen is in use the ink will flow 90 from the interior of the barrel through the feed passage 6 to the pen point in the usual manner, and by moving the valve the feeding of the ink can be controlled by the operator so that an increased or decreased 95 amount of ink will be fed to the pen point, as may be desired. When the pen is in use one of the fingers of the hand will engage the roughened surface of the slide 13, and the slide can be manipulated to move the valve and control the flow of ink to the pen point in the desired manner.

Having thus described my invention what I claim as new and desire to secure by Letters Patent is:

1. A fountain pen including a barrel, a pen point formed with an eye, ink feeding means for supplying ink to the pen point, a

valve controlling the flow of ink through the ink feeding means, a slide mounted upon the exterior of the barrel, and means connecting the slide to the valve and including 5 an element extending through the eye of the pen point.

2. A fountain pen including a barrel, a pen point formed with an eye, ink feeding means for supplying ink to the pen point, a 10 valve controlling the flow of ink through the ink feeding means, a wire connected to the valve and terminating in a lateral arm projecting through the eye of the pen point, and a slide mounted upon the exterior of 15 the barrel and connected to the arm.

3. A fountain pen including a barrel, a pen point formed with an eye, ink feeding means for carrying ink from the barrel to the pen point, a valve controlling the flow 20 of ink, a stem projecting from the valve and having a perforated head, a slide mount-

ed upon the barrel, and an arm carried by the slide and projecting through the eye of the pen point into engagement with the perforated head of the valve stem. 25

4. A fountain pen including a barrel, a plug closing one end of the barrel and formed with a pen point receiving seat and an ink feeding passage, a pen point formed with an eye and fitted in the seat of the 30 plug, a valve for controlling the flow of ink through the passage, a stem projecting from the valve and terminating in a perforated head, a slide mounted upon the barrel, and an arm carried by the slide and projecting 35 through the eye of the pen point into engagement with the perforated head of the valve stem to provide an operative connection between the slide and the valve.

In testimony whereof I affix my signature.

JOHN A. KAYE.
